UNITED STATES PATENT OFFICE.

OTTO A. PAGANDER, OF SUPERIOR, WISCONSIN.

COW-TAIL HOLDER.

1,247,870.

Specification of Letters Patent. Patented Nov. 27, 1917.

Application filed April 6, 1917. Serial No. 160,213.

To all whom it may concern:

Be it known that I, OTTO A. PAGANDER, a citizen of the United States, and resident of Superior, in the county of Douglass and 5 State of Wisconsin, have invented certain new and useful Improvements in Cow-Tail Holders, of which the following is a specification.

This invention relates to clasps and has 10 more especial reference to an improved cow tail holder.

The dominant object of the invention is to provide a clasp of the pivotal jaw type for securing the tail of a cow in a fixed 15 position whereby the disagreeable swishing thereof will be obviated, it being understood that the device is particularly adapted for use during the milking of the cow.

Another and equally important object of 20 the invention is to provide novel fastening jaws, the same being normally held in closed positions by spring means engaged therewith.

It is also an object of the invention to 25 provide a novel form of pivot for the pivotal clasping jaws, the same being provided with means for limiting the opening of the same and for securing the spring operating means arranged thereabout in proper position.

Other and further improvements and 30 novel details in the construction and arrangement of parts will be appreciated from the description to follow, which, for a clear 35 understanding of the invention should be considered in connection with the accompanying drawings forming a part hereof and wherein the preferred embodiment of the invention is shown for the purpose of 40 illustration.

In the drawings:

Figure 1 is a perspective of my improved 45 clasp as applied;

Fig. 2 is a top plan thereof; and

Fig. 3 is a fragmental detail in elevation 50 showing the arrangement of the novel form of pivot for the pivotal jaws.

Similar characters of reference are employed in all of the above described views to 55 indicate corresponding parts.

Referring now more specifically to the several figures of the said drawings there is provided a clamping jaw 1 having an extension 2 formed upon the rear portion thereof, 55 which extension is looped to provide a secondary jaw 3. The free end of the extension

is bent upon itself as at 4 to which a staple is secured adapted to engage the elongated slot in that portion of the jaw adjacent its point of pivot. As a means for normally holding the secondary jaw 2 in closed position a curved spring strip 5 is secured thereto adjacent its point of bending by rivets or other suitable devices.

A clamping jaw 6 is arranged directly beneath the clamping jaw 1 and is provided with an offset rear extremity 7, the said extremity serving as an efficient handle whereby the jaw may be moved to open position. It is to be noted, that offset portions are 70 formed within the jaws 1 and 6, intermediate their ends and serve as means for receiving the jaw pivoting device therebetween.

A plurality of disks 8 having laterally extending lugs 9 formed thereupon are arranged in opposite sides of the jaws 1 and 6 adjacent the offset portions formed therein and has passed therethrough a pivot pin 10, the opposite extremities of which are offset. The laterally projecting lugs 9 as shown in 80 the Fig. 2 are provided with curved bearing surfaces and, obviously, receive the adjacent offset portions of the jaws 1 and 6 thereon, hence, permitting free pivotal movement thereof. A coiled spring 11 is arranged 85 about the pivot pin 10 and has its opposite ends bearing upon the adjacent portions of the jaws 1 and 6 respectively and as a consequence, serve as means for normally maintaining the said jaws in closed positions.

In use, the secondary clamping jaw 3, which is flexible, is arranged about the leg of the cow and secured in position by engaging the staple in the slot of the jaw. The handle 7 is now forced in a direction to cause 95 opening of the jaw 6 whereupon the tail of the cow is inserted between the same and the jaw 1, thus, upon releasing of the handle, the cow's tail will be securely clasped therebetween and swishing of the same during 100 milking operation prevented.

Manifestly, the construction shown is capable of considerable modification and such modification as is within the scope of my claims, I consider within the spirit of my 105 invention.

I claim:

1. A clasp of the character described, including a pair of pivotal jaws having offset portions formed intermediate their ends, 110 disks arranged upon the opposite sides of said jaws adjacent the offset portions and

carrying laterally projecting lugs thereon, a pivot pin passing through the disks and between the offset portions, and spring means arranged about said pivot pin for normally maintaining the jaws in closed position.

2. A clasp of the character described, including a pair of pivotal jaws having offset portions formed therein intermediate their ends, rear extensions formed upon said jaws, one of said extensions being offset to provide a handle, the other of said extensions being looped upon itself to constitute the secondary clamping jaw, spring means engaged with the secondary clamping jaw for normally maintaining it closed, a connection carried upon the free extremity of the secondary clamping jaw engageable with the

body thereof for securing the same in closed position, a pair of apertured disks arranged upon the opposite sides of the clamping jaws adjacent the offset portions formed intermediate their ends and carrying laterally projecting lugs, a pivot pin receivable by the disks and extending between said offset portion, and a coiled spring arranged about the pivot pin, the opposite extremities of which have bearings upon the adjacent portions of each of said first clamping jaws for normally maintaining the same in closed position.

In testimony whereof, I affix my signature hereto.

OTTO A. PAGANDER.
